UNITED STATES PATENT OFFICE.

SAMUEL KORNHABER, DESIDER SAÁGHY, AND EMIL NÁDOR, OF ESZTERGOM,
HUNGARY,

KEYLESS LOCK.

Application filed November 26, 1923. Serial No. 677,097.

To all whom it may concern:

Be it known that we, SAMUEL KORNHABER, DESIDER SAÁGHY, and EMIL NÁDOR, citizens of the Hungarian Republic, and residents of 5 Petofi-utca 2, Esztergom, Hungary, have invented certain new and useful Improvements in a Keyless Lock, of which the following is a specification.

This invention relates to a keyless lock, 10 which is distinguished from locks hitherto known by the advantageous features that it can be set without taking apart and opened by the sense of hearing or touch. Locks without keys are known, which can be opened 15 after having been set to a previously determined figure. These locks have the disadvantage that their adjustment to a fresh figure is a matter of great difficulty, as in order to effect this purpose it is necessary to take 20 the lock to pieces and, after setting, to re-assemble it. As these locks usually contain a number of small component parts, it may easily happen that when they are taken apart 25 for purposes of setting, some of these parts may be lost, and apart from that the re-assembling is a matter of very minute accuracy. In contradistinction to this, the lock 30 in accordance with the present invention can be set to a fresh figure without having to be taken apart. An additional advantage is 35 that the lock can be opened even in the dark, as the setting to the determined figure can be effected by the sense of hearing or touch, that is to say that it is not necessary for the person 40 who opens the lock to see the figures, so that even the blind can operate the lock.

The accompanying drawing which illustrates three constructional forms of the lock shows, at:

40 Figure 1 a front view of the lock; Fig. 2 a front view of another construction; Fig. 3 a plan of Fig. 1; Fig. 4 a section at line A—B of Fig. 2; Fig. 5 a section at line C—D of Fig. 6 with cover plate removed; Fig. 6 a vertical section of Fig. 1; Fig. 7 a side view 45 of another construction; Fig. 8 a section of the same; Fig. 9 a section on line E—F of Fig. 8.

In the construction shown at Figs. 1, 3, 5 and 6 the casing of the lock consists of the

parts 1, 2, 3, which are retained in position by a cover plate 5, which is secured by means of a screw 4. The cover plate 5 and the parts 1, 2 and 3 are provided with three borings each, 6, 7 and 15, so that these borings 6, 7 and 15 cover each other. The borings of the parts 1 and 2 of the casing pass right through, while that of part 3 is closed underneath. Parts 1 and 3 of the casing are hollow and are closed by cover plates 8, 9. 55 Parts 1 and 3 of the casing are each furnished with two rotatable sleeves 10, 11, the circumference of which situated in the interior of the casing, is provided with teeth 12. The sleeve 10 situated in part 1 of the casing projects downwards; the sleeve 11 in part 3 of the casing projects upwards, the face of the projecting portion, i. e. the lower portion of the sleeve 10, and the upper portion of the sleeve 11, being provided with a 60 ratchet mechanism 13, 14. The sleeves 10 and 11 are provided with a pin 17 on their interior circumferential surface. The two borings 6 and 7 of part 2 of the casing receive a guide sleeve 16 which projects upwards and downwards on either side of the middle part 2. The screw 4 passes through the borings 15 and can be screwed into part 3 of the casing by means of the thread at its lower end. Between parts 1 and 2 of the 65 casing and between parts 2 and 3 of the casing are placed the rings 18, 19, provided with figures on their circumferences, the figures running, for example, from 1 to 9, a nose-piece 20 being fitted in the place of zero, 70 corresponding nose-pieces 21 being provided on parts 1 and 2 of the casing. The rings 18, 19 can be rotated around the sleeves 16, and the lower face of the ring 19 and the upper face of the ring 18 are provided with 75 ratchet wheels which engage in the ratchet mechanism 14. The upper portion of the screw 4 is surrounded by a spiral spring 22, which bears at one end against the closing plate 5 and at the other end against the cover 80 plate 8. The sleeves 10, 11 are controlled by a spring or pawl 23 engaging with the teeth 12, disposed on the circumference of the sleeves 10, 11 in the interior of parts 1 and 85 2 of the casing.

The constructional form shown in Figs. 2 and 4 differs from that shown in Figs. 1, 3, 5 and 6 to the extent that the central part 2 of the casing is thicker and that the part thereof situated between the rings 18, 19 reaches as far as parts 1, 3 of the casing. In this case the sleeve 24, which is situated in the boring 15 in part 2 of the casing is naturally dispensed with.

10 The constructional form in accordance with Figs. 7, 8 and 9 differs from the former constructions to the extent that in this case the sleeves of the ratchet gear 10, 11 are not mounted in parts 1 and 3 of the casing but 15 in the central part 2 of the casing, for which reason parts 1 and 3 are solid and the central part 2 of the casing is hollow in order to receive the ratchet sleeves 10, 11 and the ratchets 24 which are actuated by the springs 20 or pawls 23. Here also the parts of the casing are held together by a closing plate 5, which is secured by means of the screw 4, which is surrounded by a spiral spring 22. In this case also the sleeves 10 and 11 are 20 fitted internally with a pin 17. In this instance, the face of the sleeves 10, 11 is smooth, while a pin 25 is fitted on the circumference of the sleeves which projects beyond the casing 2, the said pin working in conjunction 25 with grooves 26 provided in the wall of the boring of the rings 18, 19. (See Fig. 11.)

In all the above constructional forms the upper surface of part 1 of the casing is provided with a recessed portion 27.

30 35 The lock according to the present invention is completed by the bow 28, both shanks of which are provided with longitudinal grooves 29 and circumferential grooves 30.

The method of operating the lock is as 40 follows:

The rings 18, 19 are first of all set to the 45 previously determined figure. For this purpose the closing plate 5 is turned transversely to part 1 of the casing. Part 1 of the casing now rises under the action of the spiral spring 22, so that the rings 18, 19 can be turned to the left, without their teeth engaging in the toothing 13, 14 of the sleeves 10, 11, that is to say: the sleeves 10, 11 do 50 not turn with them. When the sleeves 10, 11 are in the position of rest the pins 17 in their interior, are opposite to the longitudinal groove 29 in the bow 28, so that no obstacle exists to the insertion of the bow into the 55 lock. Thus, when the rings 18, 19 have been set, with the screw 4 loosened, the screw 4 is tightened up once more. The ratchet wheels of the rings 18, 19 now engage with the ratchet wheels 13, 14 on the face of the sleeves 10, 11. When the rings 18, 19 are set 60 in position the bow 28 is inserted, in which process the pins 17 slide along in the longitudinal grooves 29. When the bow 28 is fully inserted, the rings 18, 19 are turned to 65 the right, and the lock is thus closed, as the

sleeves 10, 11 rotate with the rings 18, 19, and the pins 17 enter the circumferential grooves 30 in the bow 28.

If it is desired to open the lock in daytime or by artificial light, the rings 18, 19 are turned to the right until the previously determined figures come below the nose-pieces 21 on parts 1 and 2 of the casing. In this case, the pins 17 enter the longitudinal grooves 29 and the bow 28 can be withdrawn.

When however the lock has to be opened in the dark, the rings are turned to the right until the nose-pieces 20 thereon come under the nose-pieces 21 on the parts of the casing, which can be detected in the dark with the finger. When this is effected, the rings 18, 19 are turned further to the right so as to set them to the previously determined figure. The friction of the spring 23 rubbing against the teeth of the sleeves 10, 11, will cause a noise during the rotation of said rings. But, as a tooth 12 corresponds to each figure, after the rings 18, 19 have been set so that the nose pieces 20, 21 are in line, they must be still further turned so that the number of clicks produced corresponds to the previously determined figure on the ring. For example, if one ring is set to the Figure 6, that ring will be adjusted to the figure required after six clicks. If the rings 18, 19 should be turned backwards in consequence of the action of the springs 23, the rings 18, 19 can be set not only by hearing, but also by impact, that is to say: by the sense of touch.

On the same pattern it is also possible to construct locks suitable for doors, boxes and other articles of furniture.

We claim:

1. A keyless lock of the kind which can be set without removing the parts thereof and can be opened by means of hearing or touch and having a plurality of casing portions assembled by a screw and character bearing rings arranged therebetween, characterized by a casing closed by a pivotal closing plate and by sleeves carried by the rings and having ratchet teeth upon their circumferential surfaces.

2. A keyless lock of the kind which can be set without removing the parts thereof and can be opened by means of hearing or touch and having a plurality of casing portions assembled by a screw and character bearing rings arranged therebetween, characterized by a casing closed by a pivotal closing plate, sleeves carried by the rings and having ratchet teeth upon their circumferential surfaces, said teeth being engaged by springs secured to a casing portion, substantially as and for the purpose stated.

3. A keyless lock of the kind which can be set without removing the parts thereof and can be opened by means of hearing or touch and having a plurality of casing por-

tions assembled by a screw and character bearing rings arranged therebetween, characterized by a casing closed by a pivotal closing plate, sleeves carried by the rings and having ratchet teeth upon their circumferential surfaces, said teeth being engaged by springs secured to a casing portion, and

a spiral spring arranged between the pivotal closing plate and a casing portion, substantially as and for the purpose stated.

SAMUEL KORNHABER.
